UNITED STATES PATENT OFFICE.

CHARLES A. TATUM, OF NEW YORK, N. Y.

DESIGN FOR A WATER-BOTTLE.

SPECIFICATION forming part of Design No. 30,432, dated March 28, 1899.

Application filed February 27, 1899. Serial No. 707,118. Term of patent 7 years.

To all whom it may concern:

Be it known that I, CHARLES A. TATUM, a citizen of the United States, residing at New York city, borough of Manhattan, county and State of New York, have invented and produced a new and original Design for Water-Bottles, of which the following is a specification.

The leading feature of my design is a water-bottle having trimmings contrasting in tint or color with the tint or color of the body of the bottle, the said trimmings having scalloped or undulated edges.

In the accompanying drawing I have shown 15 a water-bottle embodying my invention.

In the drawing, A is the bottle-body; B, the funnel or mouth; C, the strap or handle, and D the suspension-ring. The bottle is trimmed with trimmings *a*, having scalloped or undulated edges and contrasting in color or tint with the body of the bottle.

What I claim, and desire to secure by Letters Patent, is—

The design for a water-bottle substantially as herein shown and described.

CHARLES A. TATUM.
